[57] CLAIM

The ornamental design for a clip on bead for hair, as shown and described.

DESCRIPTION

FIG. 1 is a front elevational view of the clip on bead for hair of the present invention;

FIG. 2 is a rear elevational view of the clip bead for hair of FIG. 1;

FIG. 3 is top elevational view of the clip on bead for hair of FIG. 1;

FIG. 4 is a bottom elevational view of the clip on bead for hair of FIG. 1; and,

FIG. 5 is a top, front perspective view of the clip on bead for hair of FIG. 1.

The undisclosed portions of the inner surface follow the contours of the portions shown.
